UNITED STATES PATENT OFFICE.

GEORGE HENRY WHEARY, OF RACINE, WISCONSIN.

TRUNK-LOCKING MEANS.

1,212,299.

Specification of Letters Patent. Patented Jan. 16, 1917.

Application filed January 9, 1913. Serial No. 740,909.

To all whom it may concern:

Be it known that I, GEORGE H. WHEARY, a citizen of the United States, and resident of Racine, in the county of Racine and State of Wisconsin, have invented new and useful Improvements in Trunk-Locking Means, of which the following is a description, reference being had to the accompanying drawings, which are a part of this specification.

This invention relates to improvements in trunk locking means which is particularly adapted for use in connection with wardrobe trunks having a plurality of covers or doors.

Some of the wardrobe trunks now on the market are formed with side doors or covers giving access to the wardrobe section of the trunk and also with end or top doors or covers giving accessibility to other portions of the trunk. These doors or covers are secured in closed positions by independent locks which have to be independently unlocked when the trunk is opened.

It is one of the objects of the present invention to provide a trunk of the type described in which it is only necessary to unlock one of the locks with a key and upon opening the cover locked thereby lock or locks of the other cover may be unlocked by simply moving a controlling member exposed to view by the opening of first cover.

A further object of the invention is to provide a trunk having a plurality of covers with locks so constructed that any number of locks may be easily unlocked by means of one controlling member which is exposed to view by opening one of the covers.

A further object of the invention is to provide a trunk locking means in which portions of the locks are also adapted to draw the cover into close engagement with the body portion with considerable power when swung into engagement with other portions of the locks.

With the above and other objects in view, the invention consists of the improved trunk locking means and its parts and combinations as set forth in the claims, and all equivalents thereof.

In the accompanying drawing in which the same reference characters indicate the same parts in all of the views, Figure 1

is a vertical sectional view of the improved trunk locking means shown in connection with a wardrobe trunk, the trunk being shown in vertical section with the cover indicated in open position by dotted lines; Fig. 2 is a transverse sectional view thereof taken on line 2-2 of Fig. 1; Fig. 3 is an enlarged view of one of the locks shown attached to a fragmentary portion of a trunk, the view being taken from the inside of the trunk; Fig. 4 is a horizontal sectional view thereof taken on line 4-4 of Fig. 3; Fig. 5 is a detail sectional view of the lock; and Fig. 6 is a detail view of the upper end of the controlling member.

Referring to the drawing the numeral 8 indicates a wardrobe trunk, 9 the wardrobe section thereof which is hinged to the body section of the trunk and forms the side or horizontally swinging door or cover and 10 the upper cover or door which closes over and overlaps both sections of the trunk. The upper cover is hinged to the body section of the trunk and is adapted to be locked to the wardrobe section by an ordinary hasp trunk lock 11 in the ordinary manner.

The wardrobe section 9 is hinged to the body section of the trunk by hinges 12 (only one being shown) and is provided with the improved hasp locks 13 which are engaged by the hasp members 14 attached to the body section of the trunk.

The lock comprises the angular casing 15 inclosing a bolt 16 held normally in its outer locking position by means of a coiled spring 17 positioned with the casing and surrounding the stem 18 of the bolt and interposed between the shoulder 19 of the bolt and the partly closed end 20 of the casing. The bolt is provided with a projection 21 which extends through the elongated slot 22 of the casing to limit the travel of the bolt, the slot being of sufficient length to permit the desired movement of the bolt. The hasp engaging end 23 of the bolt is beveled to provide for the eyed portion 24 automatically snapping into locking engagement with the bolt 16 when the hasp member is pressed inwardly.

In order to wedgily draw the two portions of the trunk together to form a tight closure the inner edge 25 of the eyed portion 24 is formed at an angle so that when entering the lock opening 26 it will engage

the edge of the escutcheon plate 27 of the lock and draw the wardrobe section tightly to the body section of the trunk.

The lock controlling member is in the form of a bar 28 slidably positioned in guides 29 mounted on the inner surface of one of the walls of the wardrobe section. The controlling bar is located adjacent to the locks and is provided with short arms 30 projecting therefrom which are connected by chains 31 to the stems 18 of the lock bolts so that when the controlling bar is pulled upwardly both bolts connected thereto will be withdrawn from the hasp members. The hasp members are provided with springs 32 which will automatically swing the hasp members out of engagement with the lock when released.

The upper end of the controlling bar terminates at a point close to the upper opening of the trunk and is bent over to form a hooked portion or handle 33 for convenience in operating the same.

From the foregoing description it will be seen that when the trunk is locked it is only necessary to unlock the lock of the upper cover and lift said cover to gain access to the controlling member of the other locks and that these last mentioned locks may be released by pulling upwardly on the controlling member, thus providing for the opening of a trunk having a plurality of locks in a very simple manner.

What I claim as my invention is:

35 1. The combination with a trunk divided longitudinally of its length to form two hinged together members and also having a top cover member for one of the hinged together members, of locking means therefor comprising a locking means for the top cover member, a locking means for the trunk hinged together members remote from the top cover member, and a manually operable lock controlling means exposed in operable position when one of the members is swung to open position to permit the opening of the other member.

50 2. The combination with a trunk divided longitudinally of its length to form two hinged together members and also having a top cover member for one of the hinged together members, of a locking means therefor comprising a locking means for the top cover member, a locking means for the trunk hinged together members remote from the

55 top cover member, and a manually operable lock controlling means exposed in operable position adjacent to the top portion of the trunk when the top cover member is swung to open position to permit the opening of the hinged together members.

3. The combination with a trunk having an outer side cover and an outer top cover, of locking means therefor comprising a lock for one of the covers, a spring lock for the other cover, and a manually operable member positioned within the trunk and connected to the spring lock and extending to a point adjacent to the opening of the trunk covered by the cover to be first opened for unlocking the spring lock.

4. The combination with a trunk having an outer side cover and an outer top cover, of locking means therefor comprising a lock for the top cover, a plurality of locks for the side cover, and a manually operable slideable bar positioned within the trunk and connected to the locks of the side cover and extending to a point adjacent to the opening of the trunk covered by the top cover.

5. The combination with a trunk having an outer side cover and an outer top cover, of locking means therefor comprising a lock for the top cover, a plurality of locks for the side cover, and a manually operable slideable bar positioned within the trunk and having a flexible connection with the locks of the side cover and extending to a point adjacent to the opening of the trunk covered by the top cover.

6. A trunk locking means, comprising a plurality of hasp members having spring means for moving them to open position and also having projecting eyed portions, the edges of the projecting portions being formed at an angle to wedgingly draw the cover to which the hasps are connected to closed position, spring actuated bolt members positioned to enter the eyed portions of the hasps when the hasps are in closed position, and a hand actuated slideable bar positioned adjacent and connected to the bolt members for withdrawing the bolts from the eyed portions.

In testimony whereof, I affix my signature, in presence of two witnesses.

GEORGE HENRY WHEARY.
